BLOWGUN

Phillip H. Seibel, Afton, and Joseph R. Scotti,
St. Louis, Mo.

Application December 21, 1950, Serial No. 202,012

4 Claims. (Cl. 124—12)

1

This invention relates to blow guns, and more particularly to magazine-type blow guns adapted for shooting pellets such as peas, beans or the like.

The object of the invention is the provision of a blow gun of the pea-shooter type having a magazine for containing a supply of pellets, such as peas, beans or the like, adapted for shooting pellets in machine gun fashion, which may be manufactured at low cost and which is easy to load and effective in use.

In general, a blow gun of this invention comprises a barrel having an inlet section and an outlet section, and a magazine for a supply of pellets intermediate these sections. The magazine is of flat, semi-circular form having a narrow top wall, semi-circular side walls, and a narrow arcuate wall forming the bottom and end walls. The inlet section leads into the rearward end of the magazine adjacent the top of the magazine, and the outlet section leads out of the forward end of the magazine adjacent the top of the magazine. The inlet section opens into the magazine at an inlet opening adjacent the rearward end of the magazine, and the outlet section is open to the magazine at an outlet opening adjacent the forward end of the magazine. Baffle means are provided in the magazine for causing air blown in through the inlet section to flow in a stream downward from the inlet opening and thence upward and out through the outlet opening. Other features will be in part apparent and in part pointed out herein-after.

The invention accordingly comprises the elements and combinations of elements, features of construction, and arrangements of parts which will be exemplified in the structures hereinafter described, and the scope of the application of which will be indicated in the following claims.

In the accompanying drawing, in which one of various possible embodiments of the invention is illustrated,

Fig. 1 is a plan view of a blow gun embodying the invention;

Fig. 2 is a side elevation of Fig. 1;

Fig. 3 is an enlarged longitudinal vertical section taken on line 3—3 of Fig. 1, with parts broken away; and

Fig. 4 is an enlarged vertical transverse section taken on line 4—4 of Fig. 1.

Similar reference characters indicate corresponding parts throughout the several views of the drawing.

Referring to the drawings, a preferred specific

embodiment of the blow gun of this invention is shown to comprise a barrel consisting of inlet and outlet sections 1 and 3, and a magazine 5 intermediate the inlet and outlet sections. The magazine is of extended length in the direction of the length of the barrel, the inlet section 1 leading into the rearward end of the magazine adjacent its top, and the outlet section 3 leading out of the forward end of the magazine adjacent its top. The inlet section opens into the magazine at inlet opening 7, and the outlet section is open to the magazine at an outlet opening 9. A baffle 11 is located in the magazine immediately forward of the inlet opening to direct the stream of air flowing in through the inlet section downward. Another baffle 13 is located in the magazine immediately rearward of the outlet opening to guide the air stream and pellets carried along by the air stream into the outlet opening, the pellets being blown out through the outlet section 3.

More particularly, the magazine 5 is of generally flat semi-circular form, having a narrow flat top wall 15, generally semi-circular flat side walls 17 and 19 and a semi-circular arcuate wall 21 forming the bottom and ends of the magazine. The inlet section 1 of the barrel consists of a straight short length of tube extending at its forward end through and fixed in an opening 23 in the wall 21 of the magazine just under the top wall 15 of the magazine, the tube 1 preferably being parallel to the wall 15. The forward end of the inlet section tube 1 is open to provide the inlet opening 7 and is preferably beveled as indicated at 25 so that opening 7 is directed downward. The baffle 11 comprises a vertical partition fixed in position between the side walls of the magazine immediately forward of the open forward end of the inlet tube 1.

The outlet section 3 of the barrel consists of a straight length of tube considerably longer than the inlet tube 1 extending at its rearward end through and fixed in an opening 27 in the wall 21 of the magazine just under the top wall 15 of the magazine. The tube 3 is preferably parallel to the top wall 15 in line with the inlet tube 1. The rearward end of the outlet tube 3 is open to provide the outlet opening 9, and is preferably beveled as indicated at 29 so that the opening 9 is directed downward. The baffle 13 comprises a vertical partition fixed in position between the side walls of the magazine immediately rearward of the rearward end of the outlet tube 3.

The inlet and outlet tubes 1 and 3, as will be

readily understood, have an internal diameter slightly greater than the run of pellets, such as peas or beans, which are used. The magazine is made flat, its width being slightly greater than the diameter of the tubes. The baffles or partitions extend down from the top wall of the magazine a sufficient distance for guiding the air stream, leaving spaces between the lower edges of the baffles and wall 21 for the air flow. A funnel 31 is secured in an opening 33 in the top wall 15 of the magazine for loading pellets into the magazine. The funnel might be omitted, in which case the magazine would be loaded either through the inlet or outlet tube, usually the inlet tube as it is short.

In use, the magazine is loaded with pellets through the funnel 31. The funnel is then held closed by the hand. Upon blowing a continuous stream of air through the inlet tube 4, the air stream is directed downward into the magazine by the baffle 14, the change in direction being facilitated by the bevel of the forward end of the inlet tube. The air flows down and then curves up and out through the outlet tube 3, carrying with it a stream of pellets. Entrance of the pellets into the outlet tube is facilitated by the guiding action of the baffle 13 and the bevel form of the rearward end of the outlet tube. If desired, short bursts of pellets may be blown out by puffing into the inlet tube 4, rather than by blowing in a continuous stream.

In view of the above, it will be seen that the several objects of the invention are achieved and other advantageous results attained.

As many changes could be made in the above constructions without departing from the scope of the invention, it is intended that all matter contained in the above description or shown in the accompanying drawing shall be interpreted as illustrative and not in a limiting sense.

We claim:

1. A magazine-type blow gun for shooting pellets such as peas, beans or the like, comprising a magazine for pellets, the magazine being of flat, semi-circular form having a narrow top wall, semi-circular side walls, and a narrow arcuate wall forming the bottom and end walls of the magazine, an air inlet tube extending at its forward end through an opening in the rearward end of the arcuate wall of the magazine closely

adjacent the top wall of the magazine, an air outlet tube extending at its rearward end through an opening in the forward end of the arcuate wall of the magazine closely adjacent the top wall, and baffle means in the housing for causing air blown in through the inlet tube to flow in a stream downward from the forward end of the inlet tube and thence upward and out through the rearward end of the outlet tube.

2. A magazine-type blow gun for shooting pellets such as peas, beans or the like, comprising a magazine for pellets, the magazine being of flat, semi-circular form having a narrow flat top wall, semi-circular side walls, and a narrow arcuate wall forming the bottom and end walls of the magazine, an air inlet tube generally parallel to the top wall of the magazine extending at its forward end through an opening in the rearward end of the arcuate wall of the magazine closely adjacent the top wall of the magazine, an air outlet tube extending at its rearward end through an opening in the forward end of the arcuate wall of the magazine closely adjacent the top wall, and baffle means in the housing for causing air blown in through the inlet tube to flow in a stream downward from the forward end of the inlet tube and thence upward and out through the rearward end of the outlet tube.

3. A blow gun as set forth in claim 2 wherein the ends of the tubes extending into the magazine are bevelled to present downwardly opening inlet and outlet openings, and the baffle means consists of a partition immediately forward of the bevelled end of the inlet tube and a partition immediately rearward of the rearward end of the outlet tube.

4. A blow gun as set forth in claim 3, further including a funnel fixed in the top wall of magazine for loading the magazine with pellets.
